MINING MACHINE

Leon E. Simmons, Claremont, N. H., assignor to
 Sullivan Machinery Company, a corporation
 of Massachusetts

Application September 13, 1935, Serial No. 40,450

25 Claims. (Cl. 262—30)

This invention relates to mining machines, and more particularly to improvements in coal mining machines of the flexibly fed, room and pillar, floor cutter type.

5 An object of this invention is to provide an improved coal mining machine of the room and pillar type having an improved bottom shoe structure for supporting the machine for sliding movement over the mine floor, the bottom shoe structure being so formed as to facilitate discharge from the machine of the cuttings brought back from the kerf by the cutter chain. Another object is to provide an improved bottom shoe structure having associated therewith improved skid jack means whereby the machine may be tilted to change its angle in altitude. Yet another object is to provide an improved jack means for tilting the machine in a sidewise direction about an axis extending longitudinally 10 of the machine, thereby to facilitate movement of the machine over an uneven mine floor during the transverse cutting operation and for preventing binding of the cutter bar in the kerf. A further object is to provide an improved jack 15 means for tilting the machine about a transverse axis to vary the angular position of the cutter bar in the direction of its length as the machine moves over a rolling or uneven mine floor. Another object is to provide improved 20 means for impeding the conveyance of cuttings back into the kerf by the cutter chain and for guarding the cutter chain. These and other objects and advantages of the invention will, however, hereinafter more fully appear.

25 In the accompanying drawings there are shown for purposes of illustration one form and a modification thereof which the invention may assume in practice.

In the drawings,—

30 Fig. 1 is a plan view of a coal mining machine having embodied therein one illustrative form of the invention.

Fig. 2 is a rear end elevational view of the mining machine shown in Fig. 1.

35 Fig. 3 is a side elevational view of the coal mining machine as viewed from the advancing side thereof.

Fig. 4 is a plan view of the improved skid plate and jack structure.

40 Fig. 5 is a cross sectional view taken substantially on line 5—5 of Fig. 3.

Fig. 6 is a fragmentary side elevational view 45 of the mining machine as viewed from the receding side thereof.

Fig. 7 is a horizontal sectional view taken substantially on line 7—7 of Fig. 6.

Figs. 8 and 9 are fragmentary views similar to Figs. 6 and 7 showing a modified form of construction.

5 In this illustrative construction both forms of the invention are shown embodied in a coal mining machine of the flexibly fed, room and pillar, floor cutter type. The machine, in this instance, is of a reversible character having a reversible cutter chain and capable of cutting in either of opposite directions across a coal face, and the feeding and guiding means for the machine are arranged to effect feed in either direction simply by re-winding the cables on the 10 drums and rearranging the cables with respect to the cable guiding means.

The machine, as is common in room and pillar machines, has a machine frame 1 mounted on a sliding shoe structure 2 for sliding movement over the mine floor. Extending longitudinally 20 through the bottom of the frame directly above the bottom shoe structure is a chamber 3 in which is arranged an elongated horizontal plane cutter bar 4. The cutter bar is rigidly fixed within the machine frame and has its horizontal cutting portion projecting forwardly from the frame, and mounted for circulation about the margin of the cutter bar is an endless cutter chain 5. Mounted on the frame is a motor 6 having its power shaft operatively connected to 25 the cutter chain 5 for effecting circulation thereof.

A coal cutting machine of the room and pillar type, during the cutting operation, is usually fed over the mine floor and guided during 35 its feeding movement by means of feeding and guiding cables 7 and 8 wound on feeding and guiding drums 9 and 10, respectively, likewise driven by the motor 6, thereby to move the cutter bar transversely across the coal face to cut a 40 substantially horizontal kerf. During the cutting operation, the mining machine must often be moved over an undulating mine floor or so-called rolling bottom, and under such conditions it is desirable to provide means for tilting 45 the kerf cutter to vary its angle in altitude, thereby to compensate for the unevenness of the mine floor. The feeding cable is adapted to be fastened to a suitable anchor jack 11 located near the coal face at the rib, while the guiding cable 8 is fastened to an anchor jack 12 located at the opposite rib, and as the cables are wound in the machine is fed across the coal face under the control of the guiding drum 10. Ar- 50 55

ranged at the opposite front corners of the machine are guide sheaves 13, 13, and at the rearward end of the machine are guide sheaves 14, 14 and 15, 15, while mounted on the opposite sides of the machine are guide sheaves 16, and the feeding and guiding cables are adapted to be extended in various directions about these guide sheaves to effect feeding and maneuvering of the machine in the manner well understood by those skilled in the art.

Now referring to the improved bottom shoe structure, it will be noted that extending longitudinally of the machine is a centrally located elongated shoe 20 relatively narrow in width, the sides and bottom of the bottom shoe structure being laterally cut away at 21 to form the shoe. The narrow shoe 20 is formed integral with the machine frame by means of transverse connecting shoe portions 22, 23 rigidly fixed to the machine frame at the opposite ends of the latter. The rearward portion of the cutter bar 4 lies directly above the relatively narrow shoe 20, the shoe being of substantially the same width as the cutter bar, as shown in Fig. 5, and the cutter bar is rigidly secured within the machine frame by means of a block 24 projecting through a slot in the bar and rigidly bolted to the machine frame. When the mining machine is cutting from left to right, as viewed in Fig. 1, the cut-away portion 21 at the side and bottom of the bottom shoe structure at the receding side of the machine forms an elongated opening through which the cuttings brought back from the kerf by the cutter chain are expelled from the machine as the machine moves laterally over the mine floor. It will be noted that by cutting away the skid bottom as well as the side, the cuttings are discharged from the machine directly onto the mine floor, and the inner end wall of the opening formed by the front transverse portion 22 of the skid acts to impede movement of cuttings back into the kerf; and of course, as the machine is fed laterally the cuttings on the floor are left behind.

There is shown in Fig. 4 an adjustable skid jack structure comprising a bottom skid plate 25 having a smooth bottom surface adapted to slidably engage the mine floor and having pivotally connected thereto at 26 a vertical plate 27. Also pivotally mounted on the skid plate at 28 are jacks 29 each having a hook-shaped portion 30 projecting through slots in the vertical plate, and when the vertical plate is placed against the forward advancing side of the machine frame, these hook-shaped portions are adapted to interlock with the vertical side of the bottom shoe structure in the manner shown in Fig. 5. The jacks 29 are herein preferably of the hydraulic type comprising a frame 31 having secured thereto a piston 32 contained in a cylinder 33 with which the hook-shaped portions 30 are integrally formed. Mounted on the frame 31 is a pump 34 having an operating lever 35. When the pump 34 is actuated by the lever 35, hydraulic pressure may be supplied to the cylinder 33 to effect reciprocation thereof with respect to the piston 32, thereby to raise the machine frame of the mining machine into the tilted position shown in Fig. 2 with the advancing side of the machine 70 raised from the mine floor. The skid plate 25 is formed to fit substantially within the cut-away portion 21 at the advancing side of the machine so that when the machine is in its lowered position, as shown in Fig. 5, the bottom 75 surface of the skid plate is substantially flush

with the bottom surface of the sliding shoe 20. By operating one or the other of the jacks 29, the machine may also be tilted in an endwise direction about a transverse axis to move the tip end of the cutter bar either upwardly or downwardly as desired so that when the machine moves over an undulating mine floor, the cutter bar may be tilted to maintain the cutter bar substantially horizontal during the transverse cutting operation. By operating these jacks 10 the cutter bar may also be tilted to cut around obstructions in the coal. When the machine is operating in an opposite direction, that is from right to left as viewed in Fig. 1, the jack structure may be detached from the then receding 15 side of the machine and re-attached to the opposite side of the machine so that the advancing edge of the machine frame may be raised from the mine floor during cutting in the opposite direction, and at this time the opening 21 at the 20 opposite side of the machine provides a cuttings discharge opening for facilitating expulsion of the cuttings as the machine moves laterally over the mine floor.

In the modified form of construction shown in Figs. 8 and 9, the lower portion of the bottom shoe structure is cut away or slotted at 37 at a plurality of points along the length of the shoe structure, thereby to provide baffle-like strips 38 having spaced vertical portions 39. The bottom skid plate in this form of the invention may underlie the strips 38, or, if desired, may be formed with slots to receive the strips, thereby to provide skid portions projecting between the strips 38. These baffle-like strips act 35 as baffle means during the transverse cutting operation so as to impede movement of the cuttings back into the kerf as the machine is advanced across the coal face. The vertical portions 39 of these baffle-like strips also act as 40 safety means for reducing the possibility of injury to the operator, the vertical portions 39 of the strips acting as cutter chain guards. Otherwise this form of the invention is similar to that above described.

The mode of operation of the improved mining machine will be clearly apparent from the description given. When the machine is in the position shown in Fig. 1 with the feeding and guiding cables arranged to effect feed of the machine transversely across the coal face from left to right, and the feeding and guiding drums are operated to wind in their respective cables, the machine is fed bodily laterally over the mine floor. As the cutter chain 5 circulates rapidly about the margin of the cutter bar, the cuttings brought back from the kerf by the cutter chain are in part expelled through the open rear end of the cutter bar chamber 3, while a substantial portion thereof are expelled laterally through the elongated slot 21 at the receding side of the machine. As the machine moves over a rolling or uneven mine floor, the hydraulic jacks 29 may be operated to lift the forward edge of the machine frame from the mine floor so that the machine at that time is supported on the skid plate 25, and as a result, the cutter bar is tilted in a sidewise direction about an axis extending longitudinally of the machine so as to enable the machine to follow an uneven mine floor and to prevent binding of the cutter bar in the kerf. If desired, one or the other of the jacks may be operated to tilt the machine about a transverse axis thereby to move the tip end of the cutter 75

bar either upwardly or downwardly to further facilitate movement of the machine over an uneven or rolling mine floor. In the modification shown in Figs. 8 and 9, the baffle-like strips extending along the open rear side of the machine frame tend to preclude the dragging of the cuttings back into the kerf by the cutter chain, and these strips are so formed as to provide substantial openings so that the cuttings are readily discharged from the machine as the latter moves laterally over the mine floor. These and other uses and advantages of the invention will be clearly apparent to those skilled in the art.

While there are in this application specifically described one form and a modification thereof which the invention may assume in practice, it will be understood that this form and modification are shown for purposes of illustration and that the invention may be further modified and embodied in various other forms without departing from its spirit or the scope of the appended claims.

What I claim as new and desire to secure by Letters Patent is:

1. In a mining machine, a machine frame having a smooth bottom surface adapted to rest upon and slide over a mine floor, a rigid cutter bar projecting forwardly from said frame, means for feeding the machine bodily laterally over the mine floor during the cutting operation, and jack means extending longitudinally of the machine at the advancing side thereof and connected to the machine frame for tilting the machine about an axis extending longitudinally of the machine while the bottom surface of the machine frame at the receding side of the machine remains resting on the mine floor.

2. In a mining machine, a machine frame having a smooth bottom surface adapted to rest upon and slide over a mine floor, a rigid cutter bar projecting forwardly from said frame, means for feeding the machine bodily laterally over the mine floor during the cutting operation, and jack means connected to the advancing side of the machine for tilting the machine about transverse and longitudinal axes, said jack means operative to elevate the machine frame for tilting the machine about said transverse and longitudinal axes while the bottom surface of said machine frame at one end or the receding side of the machine remains resting on the mine floor.

3. In a mining machine, a machine frame having a smooth bottom surface adapted to rest upon and slide over a mine floor, a rigid cutter bar projecting forwardly from said frame, means for feeding the machine bodily laterally over the mine floor during the cutting operation, a skid plate extending longitudinally of the machine along the advancing side thereof, and jack means connected to the machine frame and engaging said skid plate for elevating the advancing side of the machine on said skid plate while the bottom surface of the machine frame at the receding side of the machine remains resting on the mine floor.

4. In a mining machine, a machine frame having a smooth bottom surface adapted to rest upon and slide over a mine floor, a rigid cutter bar projecting forwardly from said frame, means for feeding the machine bodily laterally over the mine floor during the cutting operation, a skid plate at the advancing side of the machine, and jack means for elevating the advancing side of the machine on said skid plate while the bottom surface of the machine frame at the receding side

of the machine remains resting on the mine floor, said jack means including independently operable elevating jacks between said skid plate and the opposite ends of the machine frame.

5. In a mining machine of the character described, a bottom shoe structure having its bottom and longitudinal sides cut away to provide a narrow elongated shoe on which the machine is slidably supported for movement over the mine floor, the open side of said bottom shoe structure at the receding side of the machine forming an elongated discharge opening for the cuttings brought back from the kerf by the cutter chain.

6. In a mining machine of the character described, a bottom shoe structure having its bottom and longitudinal sides cut away to provide a narrow elongated shoe on which the machine is slidably supported for movement over the mine floor, the open side of said bottom shoe structure at the receding side of the machine forming an elongated discharge opening for the cuttings brought back from the kerf by the cutter chain, a jack plate insertible in the opening in the bottom shoe structure at the advancing side of the machine, and jack means for raising the advancing side of the machine on said jack plate to tilt the cutter bar sidewise.

7. In a mining machine of the character described, a bottom shoe structure having its bottom and longitudinal sides cut away to provide a narrow elongated shoe on which the machine is slidably supported for movement over the mine floor, the cut-away side of said bottom shoe structure at the receding side of the machine forming an elongated discharge opening for the cuttings brought back from the kerf by the cutter chain, the longitudinal side opening at the receding side of the machine being formed with a series of baffle-like elements for impeding movement of the cuttings back into the kerf.

8. In a mining machine of the character described, a bottom shoe structure having its bottom and longitudinal sides cut away to provide a narrow elongated shoe on which the machine is slidably supported for movement over the mine floor, the cut-away side of said bottom shoe structure at the receding side of the machine forming an elongated discharge opening for the cuttings brought back from the kerf by the cutter chain, the longitudinal side opening at the receding side of the machine being formed with a series of baffle-like elements for impeding movement of the cuttings back into the kerf, said baffle-like elements also forming guard elements for the cutter chain.

9. In a mining machine of the character described, a bottom shoe structure having its bottom and longitudinal sides cut away to provide throughout a major portion of the length of the machine frame elongated side openings for the cuttings brought back from the kerf by the cutter chain and a narrow elongated shoe at the center of the machine frame on which the machine is slidably supported for movement over the mine floor.

10. In a mining machine of the character described, a bottom shoe structure having its bottom and longitudinal sides cut away to provide throughout a major portion of the length of the machine frame elongated side openings for the cuttings brought back from the kerf by the cutter chain, and a narrow elongated shoe at the center of the machine frame on which the machine is slidably supported for movement over the mine floor.

the mine floor, said shoe having transverse connecting frames at the front and rear ends of the machine frame, said transverse connecting frames having bottom shoe surfaces cooperating with the bottom surface of said shoe in the supporting of the machine.

11. In a mining machine, a machine frame having a smooth bottom surface adapted to rest upon and slide over a mine floor, a rigid cutter bar projecting forwardly from said frame, means for feeding the machine bodily laterally over the mine floor during the cutting operation, and a plurality of jack devices one at each end of the machine frame for tilting the machine about transverse and longitudinal axes, said jack devices operative to raise the machine frame bottom at the advancing side or one end of the machine to tilt the machine about said longitudinal and transverse axes while the bottom of the machine frame at the receding side or the opposite end of the machine frame remains resting on the mine floor.

12. In a mining machine of the character described, a bottom shoe structure having its bottom and longitudinal sides transversely slotted to provide a plurality of cuttings discharge openings, said discharge openings separated by a plurality of baffle-like elements for impeding movement of the cuttings back into the kerf.

13. In a mining machine of the character described, a bottom shoe structure having its bottom and longitudinal sides transversely slotted to provide a plurality of cuttings discharge openings, said discharge openings separated by a plurality of baffle-like elements for impeding movement of the cuttings back into the kerf, said baffle-like elements also forming guard elements for the cutter chain.

14. In a mining machine of the character described, a bottom shoe structure having its bottom and longitudinal sides partially cut away to provide a narrow elongated shoe on which the machine is slidably supported for movement over the mine floor, the open side of said bottom shoe structure at the receding side of the machine forming an elongated discharge opening for the cuttings brought back from the kerf by the kerf cutter.

15. In a mining machine of the character described, a bottom shoe structure having its bottom and longitudinal sides partially cut away to provide a narrow elongated shoe portion at the center of the machine frame, and transverse bottom shoe portions extending across the machine at the front and rear ends thereof, said central shoe portion and said transverse shoe portions slidably supporting the machine for movement over the mine floor, the open side of said bottom shoe structure at the receding side of the machine forming an elongated discharge opening for the cuttings brought back from the kerf by the kerf cutter.

16. In a mining machine of the character described, a bottom shoe structure having its bottom and longitudinal sides partially cut away to provide a narrow elongated shoe on which the machine is slidably supported for movement over the mine floor, the open side of said bottom shoe structure at the receding side of the machine forming an elongated discharge opening for the cuttings brought back from the kerf by the kerf cutter, and elevating means insertable in the opening in the bottom shoe structure at the advancing side of the machine for raising the advancing side of the machine to tilt the kerf cutter.

17. In a mining machine of the character described, a bottom shoe structure having its bottom and longitudinal sides partially cut away to provide a narrow elongated shoe portion at the center of the machine frame and transverse bottom shoe portions extending across the machine at the front and rear ends thereof, said central shoe portion and said transverse shoe portions slidably supporting the machine for movement over the mine floor, the open side of said bottom shoe structure at the receding side of the machine forming an elongated discharge opening for the cuttings brought back from the kerf by the kerf cutter, and elevating means insertable in the opening in the bottom shoe structure between said transverse shoe portions at the advancing side of the machine for raising the advancing side of the machine to tilt the kerf cutter.

18. In a mining machine of the character described, a bottom shoe structure having its bottom and longitudinal sides cut away to provide a narrow elongated shoe on which the machine is slidably supported for movement over the mine floor, the cut-away side of said bottom shoe structure at the receding side of the machine providing along its length an elongated discharge for the cuttings brought back from the kerf by the kerf cutter, and baffle-like guards for the cut-away sides of said bottom shoe structure.

19. In a mining machine, a machine frame having a smooth bottom surface resting upon and slideable over the mine floor, a kerf cutter projecting from said frame, means for feeding the machine bodily over the mine floor during the kerf cutting operation, and jack means extending longitudinally of the machine in parallelism with the kerf cutter and engageable with the mine floor at the advancing side of the machine, said jack means connected to the machine frame for elevating the forward advancing side of the machine frame bottom off from the mine floor while the frame bottom at the receding side of the frame remains resting on the mine floor.

20. In a mining machine, a machine frame having a smooth bottom surface resting upon and slideable over the mine floor, a kerf cutter projecting from said frame, means for feeding the machine bodily over the mine floor during the kerf cutting operation, and jack means extending longitudinally of and underlying the machine frame, said jack means engageable with the mine floor at the advancing side of the machine and connected to the machine frame for elevating one end of the machine frame bottom off from the mine floor while the bottom of the machine frame at the opposite end thereof remains in sliding engagement with the mine floor.

21. In a mining machine, a machine frame having a smooth bottom surface resting upon and slideable over the mine floor, a kerf cutter projecting from said frame, means for feeding the machine bodily over the mine floor during the kerf cutting operation, and jack means engageable with the mine floor at the advancing side of the machine and connected to the machine frame for elevating the forward advancing side of the machine frame bottom off from the mine floor to tilt the machine about a longitudinal axis while the frame bottom at the receding side of the machine frame remains resting on the mine floor, said jack means being operative to elevate one end of the machine frame bottom off from the mine floor to tilt the machine about a transverse axis while the opposite end of the bottom

of the machine frame remains in sliding engagement with the mine floor.

22. In a mining machine, a machine frame having a smooth bottom surface resting upon and slidable over the mine floor, a kerf cutter projecting from said frame, means for feeding the machine bodily over the mine floor during the cutting operation, and jack means having a bottom skid extending longitudinally along the advancing side of the machine and slidably engaging the mine floor, said skid connected to the machine frame at and supporting the advancing side of the machine for tilting the machine about a longitudinal axis while the bottom surface of the machine frame at the receding side of the machine remains resting in sliding engagement with the mine floor.
23. In a mining machine, a machine frame having a smooth bottom surface resting upon and sliding over the mine floor, a kerf cutter projecting from said frame, means for feeding the machine bodily over the mine floor during the cutting operation, and jack means for tilting the machine about a longitudinal axis comprising a bottom skid underlying the machine frame at the advancing side thereof and providing a sliding support for the frame, said jack means adjustable to elevate the machine frame so that its advancing side is solely supported by said bottom skid while the bottom of the frame at the

receding side of the machine remains resting in sliding engagement with the mine floor.

24. In a mining machine, a machine frame having a smooth bottom surface adapted to rest upon and slide over a mine floor, a rigid cutter bar projecting forwardly from said frame, means for feeding the machine bodily laterally over the mine floor during the cutting operation, and jack means connected to the advancing side of the machine for tilting the machine about a transverse axis to change the angle in altitude of said kerf cutter while a portion of the bottom surface of the machine frame remains resting on the mine floor.

25. In a mining machine, a machine frame having a smooth bottom surface resting upon and sliding over a mine floor, a kerf cutter projecting from said frame, means for feeding the machine bodily over the mine floor during the cutting operation, and jack means for tilting the machine about an axis extending longitudinally of the machine comprising a bottom skid underlying the machine frame along one side thereof and providing a sliding support for the frame, said jack means adjustable to elevate the machine frame so that said side of the machine is solely supported by said bottom skid while the bottom of the frame at the other side of the machine remains in sliding engagement with the mine floor.

LEON E. SIMMONS.
